CLAIM

The ornamental design for a ceiling fan as shown and described.

DESCRIPTION

FIG. 1 is a top perspective view of a ceiling fan, showing my new design;

FIG. 2 is a bottom perspective view thereof;

FIG. 3 is a bottom view thereof;

FIG. 4 is a top view thereof;

FIG. 5 is a front view thereof;

FIG. 6 is a rear view thereof;

FIG. 7 is a right-side view thereof; and,

FIG. 8 is a left-side view thereof.

Portions of the ceiling fan, motor housing, and ceiling fan environment are shown in broken lines. Portions shown in broken lines form no part of the claimed design. The ceiling fan blades are shown with a symbolic break in their length. The appearance of any portion of the ceiling fan blades between the break lines forms no part of the claimed design.
